CONFESSITIONAL PRIE-DIEU

Harry A. Baker, Harry E. Baker, and Walter C. Deako, Grand Rapids, Mich., assignors to Morgan Manufacturing Company, Grand Rapids, Mich., a corporation of Michigan

Application March 16, 1953, Serial No. 24,052

Term of patent 14 years

(Cl. D29—23)

To all whom it may concern:

Be it known that we, Harry A. Baker, Harry E. Baker, and Walter C. Deako, all citizens of the United States, residing at Grand Rapids, in the county of Kent and State of Michigan, have invented a new, original, and ornamental Design for Confessional Prie-Dieu, of which the following is a specification, reference being had to the accompanying drawing, forming a part thereof.

In the drawings:

Figure 1 is a perspective view of a confessional prie-dieu showing our new design wherein the confessional panels and screen are in the lowered position;

Figure 2 is a rear elevational view of the confessional prie-dieu shown in Figure 1;

Figure 3 is a top view of the confessional prie-dieu shown in Figure 1;

Figure 4 is a side elevational view of the confessional prie-dieu shown in Figure 1;

Figure 5 is a perspective view of the confessional prie-dieu shown in Figure 1 wherein the confessional panels and screen are in the upright position;

Figure 6 is a top view of the confessional prie-dieu shown in Figure 1 positioned as shown in Figure 5;

Figure 7 is a side elevational view of the confessional prie-dieu shown in Figure 1 positioned as shown in Figure 5; and

Figure 8 is a front elevation of the confessional prie-dieu shown in Figure 1 positioned as shown in Figure 5.

We claim:

The ornamental design for a confessional prie-dieu, as shown and described.
